[57] CLAIM

The ornamental design for a luggage case, as shown and described.

DESCRIPTION

FIG. 1 is a perspective view of a luggage case showing our new design;

FIG. 2 is a front elevational view thereof, the rear elevational view being a mirror image thereof;

FIG. 3 is a side elevational view thereof, showing the side opposite that shown in FIG. 1;

FIG. 4 is a top plan view thereof;

FIG. 5 is a bottom plan view thereof;

FIG. 6 is a perspective view of an alternate embodiment of the luggage case;

FIG. 7 is a front elevational view of the second embodiment, the rear elevational view being a mirror image thereof;

FIG. 8 is a side elevational view of the embodiment of FIG. 6 showing the side opposite that shown in FIG. 6;

FIG. 9 is a top plan view of the embodiment of FIG. 6;

FIG. 10 is a bottom plan view of the embodiment of FIG. 6;

FIG. 11 is a perspective view of a third embodiment of a luggage case showing our design;

FIG. 12 is a front elevational view of the embodiment of FIG. 11, the rear elevational view being a mirror image thereof;

FIG. 13 is a side elevational view of the embodiment of FIG. 11, showing the side opposite that shown in FIG. 11;

FIG. 14 is a top plan view of the embodiment of FIG. 11;

FIG. 15 is a bottom plan view of the embodiment of FIG. 11;

FIG. 16 is a perspective view of still a fourth embodiment of a luggage case showing our design;

FIG. 17 is a front elevational view of the embodiment of FIG. 16, the rear elevational view being a mirror image thereof;

FIG. 18 is a side elevational view of the embodiment of FIG. 16 showing the side opposite the one shown in FIG. 16;

FIG. 19 is a top plan view of the embodiment of FIG. 16; and

FIG. 20 is a bottom plan view of the embodiment of FIG. 16.
